FIG. 37

FIG. 1 is a side elevational view of a preferred embodiment of the sign structure or the like showing my new design, the other three sides being substantially mirror images of that shown;

FIG. 2 is a top plan view of such structure;

FIG. 3 is a section taken through lines 3—3 of FIG. 2;

FIG. 4 is a side elevational view of a first modification of the sign structure or the like showing my new design, the other two sides being substantially mirror images of that shown;

FIG. 5 is a corner elevational view of such modification;

FIG. 6 is a top plan view of the same;

FIG. 7 is a section taken through lines 7—7 of FIG. 6;

FIG. 8 is a front plan view of a second modification of the sign structure or the like;

FIG. 9 is a rear elevational view of such modification;

FIG. 10 is a top plan view of the same;

FIG. 11 is a front elevational view of a third modification of the sign structure or the like;

FIG. 12 is a rear elevational view of the same;

FIG. 13 is a side elevational view of such modification, the opposite side being substantially a mirror image of that shown;

FIG. 14 is a top plan view of the sign structure or the like;

FIG. 15 is a front elevational view of a fourth modification of the sign structure or the like;

FIG. 16 is a rear elevational view of such modification;

FIG. 17 is a side elevational view of the same, the opposite side being substantially a mirror image of that shown;

FIG. 18 is a top plan view of such modification;

FIG. 19 is a front elevational view of a fifth modification of the sign structure or the like;

FIG. 20 is a rear elevational view of the same;

FIG. 21 is a side elevational view thereof, the opposite side being substantially a mirror image of that shown;

FIG. 22 is a top plan view of such modification;

FIG. 23 is a front elevational view of a sixth modification of the sign structure or the like;

FIG. 24 is a rear elevational view of the same;

FIG. 25 is a side elevational view of such modification, the opposite side being substantially a mirror image of that shown;

FIG. 26 is a top plan view of such modification;

FIG. 27 is a front elevational view of a seventh modification of the sign structure or the like;

FIG. 28 is a rear elevational view of such modification;

FIG. 29 is a side elevational view of the same, the opposite side being substantially a mirror image of that shown;

FIG. 30 is a top plan view of such modification;

FIG. 31 is a front elevational view of an eighth modification of the sign structure or the like;

FIG. 32 is a rear elevational view of the same;

FIG. 33 is a side elevational view of such modification, the opposite side being substantially a mirror image of that shown;

FIG. 34 is a top plan view of this modification;

FIG. 35 is a front elevational view of a ninth modification of the sign structure or the like, the rear thereof being substantially a mirror image of that shown;

FIG. 36 is a side elevational view of the same, the opposite side being substantially a mirror image of that shown; and

FIG. 37 is a top plan view of such modification;

The standard is broken away in FIG. 1 to indicate intermediate length and fragmentarily shown in FIGS. 3—5, 7—9, 11—13, 15—17, 19—21, 23—25, 27—29, 31—33, 35 and 36 for convenience of illustration.

I claim:

The ornamental design for a sign structure or the like, as shown and described.
